Primary Examiner — Lakiya Rogers*Assistant Examiner* — Harold Blackwell, II(74) *Attorney, Agent, or Firm* — George R. McGuire;
Bond, Schoeneck & King, PLLC**(57) CLAIM**

The ornamental design for a hard case for fiber optic test equipment, as shown and described.

DESCRIPTION

FIG. 1 is a perspective view of a new and ornamental design for a hard case for fiber optic test equipment;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines in the drawings illustrate portions of the hard case for fiber optic test equipment which forms no part of the claimed design.
